SWITCH BOX HOLDER

Filed Jan. 30, 1929

UNITED STATES PATENT OFFICE

PERCIVAL L. JUDD, OF LAKewood, EARL B. ATKINSON, OF BAY VILLAGE, AND ROY A. ANDERSON, OF LAKewood, OHIO

SWITCH BOX HOLDER

Application filed January 30, 1929. Serial No. 336,041.

This invention relates to switch box holders and particularly to holders for wall switch boxes when installed in walls constructed of what is commonly termed wall board, or for boxes installed in the ordinary lath and plaster walls after the same have been finished and where it is difficult to put in the usual cross pieces between studding to which the box may be secured and which will hold the free ends of the laths cut to accommodate the switch box.

The object of my invention is to provide holders for wall switch boxes which will hold the box securely in place in walls in which it is difficult to make nails hold, to provide holders which are very inexpensive to manufacture and may be used with the ordinary wall switch boxes now in use without in any manner altering the same.

With these and such other objects in view as will be apparent from the disclosure the invention resides in all the features of novelty and combination of parts hereinafter described and particularly pointed out in the appended claims.

In the accompanying drawings Fig. 1 is a perspective view of the holder; Fig. 2 a front elevation of a switch box secured in a wall by the holders shown in dotted lines; Fig. 3 is a sectional view on line 3-3 of Fig. 2; Fig. 4 is a sectional view on line 4-4 of Fig. 2; and Fig. 5 is a fragmentary rear elevation of a switch box secured in a lath and plaster wall illustrating how the holder may be bent to hold the free ends of the laths.

In describing my invention and the manner in which it is used, reference is made to the drawings in which like reference numerals designate like parts in the several views.

The holder of my invention which is shown in perspective in Fig. 1 of the drawings and which is designated generally by reference numerals 10 comprises a relatively thin flat sheet metal strip 11 with two integral fingers 12 extending laterally from one edge and located near the center thereof. The holder may be stamped or otherwise cut from sheet metal in any known manner.

It will be obvious as the description proceeds that there may be only one wide finger

12 or more than two, but it has been found that the device as shown is preferred.

The wall switch box 15 shown in the drawing is the common box now on the market with the attaching ears 16 which in the particular type illustrated are adjustable, and are secured to the box 15 by screws 17. The outwardly projecting portions 18 of the ears 16 are ordinarily provided with apertures 19 adapted to receive the nails or screws by which the box is secured to the wall.

In securing the box 15 in place with the holders 10, the wall board 20 is provided with the usual aperture 21 slightly larger than the box 15 to be inserted. By holding to the fingers 12 a holder 10 is inserted through the aperture, with the fingers projecting outwardly therethrough and positioned against one side of the aperture 21 with the inner edge of the strip 11 pulled tightly against the back side of the wall board the fingers 12, or one of them is bent over the front of the board, as shown in dotted lines in Fig. 4. One holder is placed at each of the two vertical sides of the opening 21. The box 15 is then pushed in place and with the ears 18 pressed tightly against the front of the wall board 20 the fingers 12 of the holder are bent inwardly over the edge of the box 15 and into the position shown in full lines in Fig. 4. The box is now held securely in its place. The edge of the strip 11 bites into the back of the board 20 so that when properly put in they will not slip up or down after the fingers 12 are bent into place over the edge of the box.

It is preferable to bend the ends of the strip 11 in an arc, as shown in Fig. 2 before the holder is inserted in the wall, the outer laterally deflected ends tending to prevent tilting of the strip when they are initially held in place prior to inserting the box 15 and provide a more substantial bearing against the rear of the wall surface. The flexibility of the strip 11 also permits it to be bent around obstacles in the wall so that these holders can be used in places where it would be almost impossible to put in reinforcing blocks.

In Fig. 5 the holder 10 is illustrated in use in a wall constructed with lath and plaster.

By bending the ends of the strip 11 into a U-shape the free ends of the intermediate lath 25 are securely held in place and the outer ends of the strip 11 engage the laths 25 which have not been cut. The laterally extending ears 18 on the box being pressed tightly against the front side of this lath, the box 15 is held tightly in place.

It is of course obvious that the strip 11 may be long or short and the fingers 12 made long enough to accommodate any thickness of wall. The box 15 is readily removed by merely bending the fingers 12 away therefrom.

15 The holders 10 are usually made from thin sheet iron but any sheet metal which is flexible and still sufficiently strong to answer the purpose may of course be used.

It is obvious that the holder 10 may be used 20 to hold any receptacle in an opening in the same manner as illustrated with the switch box.

Having thus described my invention, what I claim is:

25 1. A switch box holder, adapted to support a switch box in an opening in a support comprising a thin flat sheet metal strip having a lateral extension projecting from one edge thereof adapted to engage over the outer edge of a switch box.

30 2. A switch box holder, adapted to support a switch box in an opening in a support comprising a thin flat sheet metal strip adapted to be bent in any desired shape, having lateral extensions projecting from one edge thereof, adapted to be bent to engage over the outer edge of a switch box.

35 3. In combination with a support having an opening, a receptacle arranged in said opening, means for preventing rearward movement of said receptacle in said opening and a device having a portion engaging the rear side of said support and means extending therefrom engaging the front edge of said receptacle for rigidly holding said receptacle in place, said device being non-resilient in the direction of movement of said receptacle when inserted into or taken out of said support.

40 4. In combination with a support having an opening therein and a receptacle fitting into said opening, of means for rigidly securing the same therein comprising means cooperating with said receptacle engaging the support for preventing rearward movement of said receptacle in said opening and means engaging the rear side of said support having a member extending outwardly between said receptacle and the edge of said opening and engaging said receptacle for rigidly holding the same in said support, this last mentioned member being non-resilient in a direction perpendicular to the plane of said support.

45 5. In combination with a support having

an opening therein, a receptacle fitting into said opening having means engaging said support preventing rearward movement thereof in said opening, means for preventing outward movement of said receptacle in 70 said support comprising a member engaging the rear side of said support, an extension secured thereto passing through said opening and engaging the front of said receptacle, said last mentioned means being non-resilient 75 in the direction of movement of said receptacle when inserted into said opening whereby said receptacle is rigidly secured in place.

6. In combination with a support having an opening therein, a receptacle having projections thereon positioned in said opening with the projections engaging the front side of the support, a thin sheet metal strip having a lateral extension projecting outwardly from one edge thereof engaging the rear side 80 of said support, said lateral extension projecting outwardly between said receptacle and said support and engaging over the front edge of said receptacle whereby the receptacle is rigidly secured in place.

7. In combination with a wall having an opening, a wall switch box positioned in said opening and having ears engaging the front side of said wall, a relatively thin sheet metal holder comprising a strip having a lateral 95 extension projecting from one edge thereof outwardly between the switch box and wall, the strip engaging the rear side of said wall and the extension engaging the front edge of said switch box whereby the same is rigidly 100 secured in place.

In testimony whereof, we hereunto affix our signatures.
